COOLING BED

Richard W. Young, Worcester, Mass., assignor to
 Morgan Construction Company, Worcester,
 Mass., a corporation of Massachusetts

Application May 3, 1944, Serial No. 533,823

5 Claims. (Cl. 80—48)

1

This invention relates to cooling beds for the reception of hot rolled metal bars, and more particularly to the construction and arrangement of mechanism whereby the bars may be moved in a broadside direction across the bed.

One form of cooling bed in common use comprises a series of spaced parallel substantially horizontal skids forming a support for the bars, which extend at right angles with the skids. These bars may be in the form of billets, slabs, I-beams, channels, and various other rolled shapes. They are usually conveyed to the cooling bed by a roller table and then transferred broadside from the table to the skids by a so-called "straight edge pusher." The further broadside movements of the bars along the skids, and their discharge from the skids, are brought about by means of reciprocating devices commonly known as "go-devils" located between the skids and having upwardly projecting dogs for engagement with the bars.

Certain difficulties have been encountered in the operation of these go-devils as heretofore constructed. The dog has usually been pivotally mounted and counterweighted or otherwise biased toward its raised position. Consequently during the rearward travel of the go-devil beneath the bars, the dog is depressed by its engagement with the bottom surfaces of the bars. This is undesirable, particularly in the case of various alloys, since it causes scratching of the bars. It is frequently necessary to move a group of bars along the cooling bed and then to separate this group into smaller groups or to withdraw the foremost bar from the group, and perhaps to discharge this bar from the skids. This mode of operation requires some selectively operable means for holding the go-devil dog in a depressed position while it travels forwardly beneath the bars. Such means has been known heretofore, but it has been necessary to move the go-devil through its entire forward stroke in order to release the dog, and then move the go-devil rearwardly until the dog is in position to engage the particular bar which has been selected. This involves a great waste of time, since the go-devil must be moved through a very considerable distance merely for the purpose of releasing the dog.

It is accordingly one object of the invention to provide a cooling bed having a reciprocable go-devil, the go-devil having a dog thereon for pushing engagement with the bars on the cooling bed, and the parts being so constructed and arranged that the dog will be withdrawn from

contact with the bars during the rearward travel of the go-devil.

It is a further object of the invention to provide a cooling bed go-devil having a bar-pushing dog thereon which will be held positively in a depressed position during its rearward travel and positively in a raised position during its forward travel.

It is a further object of the invention to provide a cooling bed go-devil having a bar-pushing dog thereon which can be locked in a depressed position during its forward travel and released at any desired point in such forward travel to engage a selected bar.

15 With these and other objects in view, as will be apparent to those skilled in the art, the invention resides in the combination of parts set forth in the specification and covered by the claims appended hereto.

20 Referring to the drawings illustrating one embodiment of the invention and in which like reference numerals indicate like parts,

Fig. 1 is a plan view of a go-devil, shown in partial section on the line 1—1 of Fig. 2;

25 Fig. 2 is a longitudinal section taken on the line 2—2 of Fig. 1, showing the positions normally assumed by the various parts during forward travel of the go-devil, the bar-pushing dog being raised;

30 Fig. 3 is a view similar to Fig. 2, but showing the positions assumed by the various parts during rearward travel of the go-devil;

Fig. 4 is a view similar to Fig. 3, but illustrating the effect of a locking cam as the go-devil approaches its rearward travel limit;

35 Fig. 5 is a view similar to Fig. 2, but showing the positions assumed by the various parts during forward travel of the go-devil with the bar-pushing dog locked in a depressed position;

40 Fig. 6 is a view of the frame of the go-devil, taken in section on the line 6—6 of Fig. 7;

Fig. 7 is a section on the line 7—7 of Fig. 6;

Fig. 8 is a perspective view of a locking pawl;

Fig. 9 is a perspective view of a supporting link;

45 Fig. 10 is a perspective view of a connecting link;

Fig. 11 is a perspective view of a supporting and driving link;

50 Fig. 12 is a perspective view of a bell crank lever;

Fig. 13 is a perspective view of a bar-pushing dog;

Fig. 14 is a side elevation of a cooling bed;

Fig. 15 is a plan view of the cooling bed; and

2

Fig. 16 is a front end view of the go-devil and the adjacent skids.

As shown in Figs. 14 to 16, the cooling bed illustrated comprises a series of spaced parallel horizontal skids 20 which are supported by I-beams 21 therebeneath. Two go-devils 22 are provided at opposite sides of the cooling bed to move the rolled metal bars B broadside along the skids. Each go-devil is located between two adjacent skids, and it is slidably supported by a pair of angle members 24 carried by brackets 25 on the adjacent I-beams 21. These angle members provide a track along which the go-devil may be reciprocated. A flexible element in the form of a wire rope 26 extends forwardly from each go-devil 22 and downwardly around an idler sheave 28 at the front or discharge end of the cooling bed. The rope 26 then extends rearwardly, makes several turns around a drum 29, and continues rearwardly to an idler sheave 30 at the rear or receiving end of the cooling bed. The rope passes upwardly around the sheave 30 and then forwardly to the go-devil. The two drums 29 are secured to a common shaft 32 which is driven by a reversible electric motor 33 through suitable gearing 34. Each of the rear sheaves 30 is mounted on the upper end of an upright arm 36 which is pivoted at its lower end and urged rearwardly by a tension spring 37. This construction holds the ropes sufficiently taut and takes up any stretch in the ropes. By means of suitable and well known controls, the operator can cause the motor 33 to rotate the shaft 32 in either direction, so that the go-devils may be moved either forwardly or rearwardly and stopped in any desired position. A roller table 38 is provided at the front end of the cooling bed to receive the bars as they are pushed from the skids.

Referring now to Figs. 1 to 7, it will be seen that each go-devil 22 comprises an elongated hollow frame 40 shaped substantially as an inverted U in cross section and provided with laterally projecting wing portions 41 for engagement with the guide rails 24. The upper surface of this frame is positioned slightly below the upper surfaces of the cooling bed skids 20, and at the front end of the frame there is provided a dog 42 which can be projected upwardly above the skids to serve as a bar pushing device or withdrawn downwardly below the upper surfaces of the skids to avoid engagement with the bars B.

The various parts are so constructed and arranged that the dog 42 will be withdrawn or retracted during rearward travel of the go-devil and projected upwardly during forward travel of the go-devil. For this purpose the dog 42 is pivotally mounted between the front ends of two arms 43 which extend forwardly from a bell crank lever 44 fulcrumed on a transverse pin 45 in the front portion of the frame 40. The lever 44 is formed with two downwardly extending arms 46. The dog 42 is provided with a counterweight in the form of a rearwardly extending tail-piece 48. The frame 40 carries a transverse pin 49 beneath this tail-piece to engage and support the same when the dog is retracted as shown in Figs. 3, 4 or 5. When the dog is raised, as shown in Fig. 2 it will engage the front edge of the upper wall of the frame 40 and thus be firmly braced to push against the bars. A bifurcated lever 51 is fulcrumed at its upper end on a transverse pin 52 within the rear portion of the frame 40, and a similar bifurcated lever 53 is fulcrumed at its upper end on a transverse pin 54 within the frame 40 in front of the lever 51. The lower ends of

the levers 51 and 53 are connected by a horizontal link 56 which is bifurcated at its opposite ends. The rear end of this link is connected to the lever 51 by a pin 57, and the front end of the link 56 is connected to the lever 53 by a pin 58. The ends of the rope 26 are attached to the central portions of the pins 57 and 58, and the arrangement is such that by moving the rope forwardly or rearwardly a corresponding movement will be imparted to the link 56. In order to limit this lost motion of the link 56 with relation to the frame 40, the interior of the frame is formed with a pair of opposed upright ribs 60 at the rear of the lever 53 and with a pair of opposed ribs 61 in front of the lever 53. These ribs provide abutments against which the lower end of the lever 53 will strike as it swings forwardly or rearwardly. This swinging motion of the lever is utilized to actuate the dog 42, and for this purpose a substantially horizontal link 62 is provided to connect the lever 53 with the downwardly extending arms 46 of the bell crank lever 44.

With the construction as so far described, when the rope 26 moves forwardly the lever 53 will swing forwardly to engage the ribs 61 and thus raise the dog 42, as shown in Fig. 2. Hence as the go-devil travels forwardly, the dog 42 may push a bar ahead of it along the skids 20. When the motor 33 is reversed and the rope 26 moves rearwardly, the lever 53 will swing rearwardly to engage the ribs 60 and thus lower the dog 42, as shown in Fig. 3. Consequently during rearward travel of the go-devil the dog will be withdrawn downwardly so that it cannot rub against and scratch the rolled bars on the skids.

At certain times it may be important to move the go-devil forwardly beneath some of the bars without disturbing these bars. This is accomplished by providing a selectively operable locking device capable of holding the dog 42 in a retracted position during forward movement of the go-devil. For this purpose two pawls 65 are pivotally secured to opposite sides of the link 56 by means of a transverse pin 66, so that they may normally hang downwardly by their own weight, as shown in Figs. 2 and 3. The rear surface of each rib 60 is formed with a shallow notch 67 so positioned that when the pawls are swung forwardly and upwardly their pointed front ends 50 may enter the notches. A stationary cam 69 (Figs. 4 and 14) is mounted at the rear of the cooling bed in front of each rear idler sheave 30 and in the path of the pawls 65. When the go-devil is moved rearwardly far enough to bring the pawls into engagement with this cam 69, as shown in Fig. 4, the pawls will be swung upwardly to bring their front ends close to the notches 67. Then as the rope 26 is moved forwardly, these front ends of the pawls will engage the notches 55 after only a slight forward movement of the levers 51 and 53 relative to the frame 40 and thus hold the dog 42 in a retracted position as shown in Fig. 5. While the dog will be raised slightly above the position assumed during rearward travel, it will still be below the tops of the skids 20. The pawls 65 will remain in engagement with the notches 67 even after they have left the cam 69, so long as there is a forward pull on the rope 26, but even a momentary reversal of the pull will serve to release the pawls and permit them to drop out of the notches. Consequently when the rope is again moved forwardly the dog 70 42 will be raised to the position shown in Fig. 2.

The operation of the invention will now be apparent from the above disclosure. The bars B

will be deposited on the skids 20 by the usual straight edge pusher, and the go-devils 22 will be used to slide the bars broadside along the skids and to discharge them on to the roller table 38. By operating the motor 33 in a forward or reverse direction, the go-devils can be moved forwardly or rearwardly as desired. During rearward travel of the go-devils the links 56 will assume a rearward position relative to the frames 40, and the dogs 42 will be depressed, as shown in Fig. 3, so they may pass beneath the bars B without touching the same. When the go-devils reach a desired position, the operator will stop the motor 33 and start it in a forward direction. The ropes 26 will thereupon carry the links 56 forwardly relative to the frames 40 and elevate the dogs 42, as shown in Fig. 2. Thus as the go-devils move forwardly, the dogs 42 will engage a bar and push it broadside ahead of them. At times a large group of bars may be pushed forwardly at the same time, and the operator may then wish to separate one or more bars from the front of this group. To accomplish this he will first move the go-devils rearwardly to bring the pawls 65 into contact with the cams 69, raising these pawls, as shown in Fig. 4. Then as the go-devils are again moved forwardly the pawls 65 will engage the notches 67, as shown in Fig. 5. This will prevent forward movement of the links 56 relative to the frames 40, and the dogs 42 will remain below the tops of the skids 20 and can accordingly travel forwardly beneath the bars. When the go-devils reach a desired position the operator will stop the motor 33 and momentarily reverse or "jog" the same. This will release the pawls 65 and they will drop away from the notches 67. Consequently upon resumption of forward travel of the go-devils, the dogs 42 will be elevated above the skids and into pushing engagement with a selected bar.

Having thus described my invention, what I claim as new and desire to secure by Letters Patent is:

1. A cooling bed comprising a series of skids for the reception of hot metal bars, an elongated go-devil frame movable longitudinally forwardly and rearwardly adjacent said skids, a dog mounted on the forward end of the frame, a link pivotally connected at its upper end to the frame and arranged to swing in a generally forward and rearward direction through a limited lost motion relative to the frame, actuating means movable forwardly and rearwardly beneath the frame and connected to the lower end of the link, and connecting means extending forwardly from the link to the dog arranged to lower the dog below the tops of the skids when the link swings rearwardly and to raise the dog above the tops of the skids when the link swings forwardly to push a bar broadside along the skids.

2. A cooling bed comprising a series of skids for the reception of hot metal bars, a go-devil frame movable forwardly and rearwardly adjacent said skids, a dog mounted on the frame, actuating means movable forwardly and rearwardly adjacent the frame, means providing a lost motion connection between the actuating means and the frame, means providing a positive connection between the actuating means and the dog to lower the dog below the tops of the skids when the lost motion is taken up during rearward travel and to raise the dog above the tops of the skids when the lost motion is taken up during forward travel to push a bar broadside along the skids, a movable device associated with the lost motion connection and adapted to prevent the

taking up of the lost motion during forward travel of the go-devil and thereby to maintain the dog below the tops of the skids, and means to move the device into operative position automatically upon movement of the go-devil rearwardly beyond a predetermined position.

3. A cooling bed comprising a series of skids for the reception of hot metal bars, a go-devil frame movable forwardly and rearwardly adjacent said skids, a dog mounted on the frame, actuating means movable forwardly and rearwardly adjacent the frame, means providing a lost motion connection between the actuating means and the frame, means providing positive connection between the actuating means and the dog to lower the dog below the tops of the skids when the lost motion is taken up during rearward travel and to raise the dog above the tops of the skids when the lost motion is taken up during forward travel to push a bar broadside along the skids, a device associated with the lost motion connection and movable between an inoperative position and an operative position, the device being arranged when in its operative position to prevent taking up of the lost motion during forward travel of the go-devil and thereby to maintain the dog below the tops of the skids, the device being biased toward its inoperative position, and means to move the device into operative position in opposition to its bias automatically upon movement of the go-devil rearwardly beyond a predetermined position, the lost motion connection being arranged to retain the device in its operative position during the ensuing forward travel of the go-devil and to release the device upon momentary reversal of the actuating means.

4. A cooling bed comprising a series of skids for the reception of hot metal bars, a go-devil frame movable forwardly and rearwardly adjacent said skids, a dog mounted on the frame, actuating means movable forwardly and rearwardly adjacent the frame, means providing a lost motion connection between the actuating means and the frame, means providing a positive connection between the actuating means and the dog to lower the dog below the tops of the skids when the lost motion is taken up during rearward travel and to raise the dog above the tops of the skids when the lost motion is taken up during forward travel to push a bar broadside along the skids, a pivotally supported pawl associated with the lost motion connection and movable between an inoperative position and an operative position, the pawl being arranged when in its operative position to prevent taking up of the lost motion during forward travel of the go-devil and thereby to maintain the dog below the tops of the skids, the pawl being biased by gravity toward its inoperative position, and a stationary cam located in the path of the pawl as the go-devil moves rearwardly beyond a predetermined position and arranged to swing the pawl into its operative position, the lost motion connection being arranged to retain the pawl in its operative position during the ensuing forward travel of the go-devil and to release the pawl upon momentary reversal of the actuating means.

5. A cooling bed comprising a series of skids for the reception of hot metal bars, a go-devil frame movable forwardly and rearwardly adjacent said skids, a dog mounted on the frame, actuating means movable forwardly and rearwardly adjacent the frame with a limited amount of lost motion between the actuating means and the frame, means providing a positive connection

between the actuating means and the dog to lower the dog below the tops of the skids when the lost motion is taken up during rearward travel and to raise the dog above the tops of the skids when the lost motion is taken up during forward travel to push a bar broadside along the skids, a pawl mounted on the actuating means and normally depending therefrom by gravity, a stationary cam located in the path of the pawl as the go-devil moves rearwardly beyond a predetermined position and arranged to raise the pawl, and means on the frame providing an abutment in position to be engaged by the raised pawl to prevent taking up of the lost motion during forward travel of the go-devil and thereby to maintain the dog below the top of the skids, the abutment being shaped to retain the pawl in its raised position as the forward travel continues and to

release the pawl upon momentary reversal of the actuating means.
